UNITED STATES PATENT OFFICE.

JOHN KAUT, OF ST. LOUIS, MISSOURI.

PHOTOGRAPHIC-PRINTING APPARATUS.

No. 844,680.

Specification of Letters Patent.

Patented Feb. 19, 1907.

Application filed October 31, 1906. Serial No. 341,474.

To all whom it may concern.

Be it known that I, JOHN KAUT, a citizen of the United States, residing at St. Louis, State of Missouri, have invented certain new and useful Improvements in Photographic-Printing Apparatus, of which the following is a full, clear, and exact description, reference being had to the accompanying drawings, forming a part hereof.

10 My invention has relation to improvements in automatic clock-controlled actuating mechanism for shutters for photographic-printing frames; and it consists in the novel construction and arrangement of parts more 15 fully set forth in the specification and pointed out in the claims.

In the drawings, Figure 1 is a front elevation of my invention. Fig. 2 is a vertical middle longitudinal section on line 2 2 of 20 Fig. 1, showing the shutters open. Fig. 3 is a horizontal section on line 3 3 of Fig. 1, with shutters open. Fig. 4 is a similar section with shutters closed. Fig. 5 is a vertical section on line 5 5 of Fig. 3, showing the 25 clock controlling mechanism. Fig. 6 is a similar section on line 6 6 of Fig. 4. Fig. 7 is a face view of the clock mechanism with front wall partly broken away, and Fig. 8 is a perspective view of a reducing-frame for the 30 main carrier-frame for holding a smaller-sized printing-frame.

The present invention is an improvement on the photographic-shutter device shown in my United States Patent No. 836,928, of 35 November 27, 1906, and has for its object to control the closing movement of the shutters by a clock or time mechanism set to operate for any number of seconds or minutes of exposure of the printing-plate to the light by 40 which the printing is effected. In its generic contemplation the present improvement does not differ from the patented one, since, like it, the main object is to effect the opening of the shutters for an exposure movement of 45 the printing-frame and to close the shutters upon conclusion of the printing operation.

The advantages of the invention will be better apparent from a detailed description thereof, which is as follows:

50 Referring to the drawings, 1 represents a box or hood forming the front extension of the bellows 2, by which the distance of the rear light-chamber 3 from the printing-frame is regulated. These features are well known 55 and require no detailed description. The rear of the box 1 is closed by a translucent or

frosted diffusion-plate 4 for subduing in a measure the rays emanating from the electric lamp 5. Hinged along the front upper edge of the box 1 and swinging in a vertical 60 plane is a carrier-frame "6," so termed for convenience, since it serves to support or carry the printing-frame 7, holding the negative and sensitized plate or film,) which not only carries the printing-frame, but may temporarily support a smaller or reducing carrier-frame 6', Fig. 8, for holding a smaller printing-frame. The frame 6' may in turn support a still smaller reducing-frame, according to the size of the print required. 65

The printing-frame is held in position by having its upper member inserted behind the depending portion of a bent plate or strip 8, secured to the carrier-frame, the upper extension or arm of said plate being secured to 70 the adjacent end of a contracting spring 9, whose opposite end is coupled to an eyebolt or post 10, mounted on the box 1. The normal tendency of the spring 9 is to oscillate or swing the carrier-frame outwardly, as seen 75 by the dotted position of Fig. 2. Hinged to the sides of the front of the box 1 are the shutters or doors 11, the free vertical edge of one of the doors being provided with a strip 12 for covering the joint between the shutters 80 when closed, (this door in practice closing a fraction of a second after the opposite door,) each door or shutter being coupled near the bottom to the adjacent sides of the carrier-frame by means of links 13 13, (the link connecting the door with the strip 12 being a trifle, but imperceptibly, longer to allow for the later closing above referred to to give the strip 12 opportunity to close over the opposite door.) 85

It is obvious from the foregoing connections that as the frame 6 is swung outwardly under the tension of the spring 9 it will draw the shutters to a closed position, and as the frame is forced inwardly toward the box 1 it 90 will automatically force the shutters to an open position. The latter result follows when the printing-frame is positioned for the printing operation. The operator first inserts the printing-frame 7 into position behind the 95 terminal extension of the strip 8, Fig. 2, and forces the carrier-frame 6 inwardly, whereupon the shutters are forced to an open position to admit the light from the lamp 5 to the plate. In being thus forced back the 100 carrier-frame is locked to what may be termed the "printing" or "exposing" position by 105

the shoulder 14 of a spring locking-latch 15, fixed at one end to the box 1, Figs. 1, 2, 3, 4, the plate being thus exposed to the light until the latch 15 is retracted, Fig. 4, when the spring 9 will automatically force the carrier-frame, with its printing-frame, outwardly, the shutters closing automatically with such movement. I accomplish the retraction of the spring-latch 15 after a certain time exposure of the plate by suitable clock mechanism, which can be set to expose the plate for any number of seconds. This feature of the invention I will now describe.

The clock employed is of any species of alarm-clock C, (though any kind will answer the purpose,) and no detail description of the works will be here given, as it forms no part of the present invention. The escapement e, to which the pendulum p is coupled, is provided with an arm 16, which is availed of in the stopping of the clock at the proper moment. Mounted about and tightly embracing the winding-arbor 17 of the clock mechanism is a sleeve 18, to the outer end of which is secured an index or pointer 19, coöperating with a dial D on the face of the clock-casing, said dial being marked off by suitable divisions representing five (5) seconds, (the intermediate divisions being herein omitted, though they could also be indicated.) The pointer is provided with a wing 20, by which it may be seized and turned opposite any mark on the dial, the sleeve 18 turning with the pointer under the circumstances. It may be stated in passing that the sleeve 18 embraces the winding-arbor 17 with sufficient friction so as to turn with the latter in the running of the clock, but is still sufficiently loose to permit the operator to turn the sleeve independent of the arbor when occasion requires the setting of the pointer to any given division-mark on the dial. To avoid reading the dial in the dusk or in the dark, any given division may be indicated by a peg 21, which is inserted into an opening 22 of the division-mark, the operator knowing when he has reached the proper mark by feeling the peg, (to which the pointer can then be set.) The pointer once set and the clock mechanism released, the pointer turns in unison with the winding-arbor until the clock is stopped at the end of the time exposure.

The manner of stopping the clock is effected by the following mechanism: The inner end of the sleeve 18 is provided with a cup-shaped disk 23, having a triangular notch n cut in the path of its periphery; the base of the triangle being parallel to the axis of rotation of the disk or axis of the arbor 17, Fig. 5. Now fixed at one end to the inner face of the front of the clock-casing is a high-tension spring-arm 24, having a central loop or ring 24' loosely enveloping the sleeve 18, the free end of said arm or retracting-spring 24 being

coupled to the inner end of a link 25, loosely playing through the wall of the clock-casing, the outer end of said link passing loosely through the free end of the weaker spring or locking-latch 15 and terminating in a hook 25' for engaging said latch at the proper moment, as presently to appear. The latch 15 is connected to the outer end of a reciprocating intercepting-rod 26, which in its inner movement into the clock has its inner end shoved in the path of the arm 16, oscillating with the escapement e, and stops the clock mechanism. The arm 24 is provided with a wing 27, whose rear edge rides along the edge of the disk 23 until it slips off therefrom into the notch n under the resiliency of the said arm, this movement drawing on the link 25, whose hook 25' in turn engages and pulls on the latch 15, disengaging the shoulder 14 thereof from the frame 6 when the spring 9 forces the latter outwardly, the shutters being simultaneously swung to a closed position. K represents the winding-key.

The operation of the mechanism may now be more fully described. In setting the index or pointer 19 to any given number or division on the dial D the sleeve 18 is necessarily rotated about the winding-arbor 17, so that the edge of the disk 23 necessarily travels along the adjacent end of the wing 27, carried by the retracting-arm 24, bringing the wing to a variable distance from the notch n, according to which division the pointer has been set. Once set, however, the pointer 19, sleeve 18, disk 23, and arbor 17 revolve as a unit with the release of the clock mechanism. Now as long as the wing 27 rides on the edge of the disk 23 the arm 24 will be held forced outwardly (against its own resiliency) and while in this position, Fig. 5, will keep the intercepting rod 26 out of the path of the arm 16, coupled to the escapement, permitting the clock to run. With such outward movement of the retracting-arm 24 the link 25 will be shoved outwardly, thereby releasing the latch 15, which will thus be free to automatically lock the carrier-frame in "exposure" position the moment the printing-frame is inserted therein and the parts forced inwardly toward the box 1 to allow the shoulder 14 to engage the carrier-frame and retain the shutters in an open position, as already described. Thus with the shutters swung and locked to open or exposure position and with the pointer set to the "5," "10," or "15" second or other division mark on the dial the clock mechanism will revolve the pointer, its sleeve, and disk as a unit until the zero on the dial is reached, at which time the wing 27 of the retracting-arm comes opposite the notch n, into which it is forced by the resilient action of the more powerful spring-arm 24, when by the inward-springing movement of said arm the link 25 and spring-latch 15, coupled thereto, are drawn inward, where-

by the rod 26 is forced inwardly by the latch in the path of the arm 16, coupled to the escapement, and the clock comes to a stop. At the same time the less powerful spring or latch 15 is pulled out of engagement with the frame 6, whereupon the spring 9 forces the carrier-frame outwardly, and the shutters close at the same time. The printing-frame can then be removed and another inserted, whereupon the pointer can be moved back to its proper division-mark, and with the inward movement or oscillation of the carrier-frame the latter again becomes engaged by the latch. Of course in rotating or setting the pointer back to its initial position opposite the proper division-mark on the dial D rotation is imparted to it in the direction of its regular travel, corresponding to that indicated by the curved arrows in Figs. 2 and 7, (this direction being opposite to that of the winding of the clock,) in which movement the wing 27 rides up the curved inclined wall of the notch *n* of the disk 23 until it is forced onto the outer edge of the disk, by which time the retracting-arm 24 is again forced outward the necessary distance, Fig. 5, to release the clock and to release the latch 15 from the hooked end of the link 25, by which said latch was previously retracted out of engagement with the carrier-frame. The clock being again free to run, the exposure continues until the wing 27 again comes opposite the notch *n*, when the carrier-frame will again fly outwardly to its released position, closing the shutters in such movement. To reduce the size of the original frame 6, a reducing-frame 6' may be inserted into it, the latter being provided with means for supporting a correspondingly-reduced printing-frame, as clearly obvious from Fig. 8 of the drawings.

Having described my invention, I claim—

1. In a photographic-printing apparatus, the combination with a movable carrier-frame, doors or shutters adapted to close and open according to the movement of the frame, means for retaining the shutters in an open position during the exposure of the printing-plate, and clock-controlled devices for closing the shutters and terminating the exposure.

2. In a photographic-printing apparatus, the combination of a movable carrier-frame, shutters adapted to exclude the light-rays upon movement of the frame in one direction, and to admit the light upon a movement in the opposite direction, means for locking the carrier-frame for the exposure movement of the shutters, and mechanism for automatically releasing the frame and closing the shutters at the conclusion of the exposure.

3. In a photographic-printing apparatus, in combination with suitable movable supporting means for the negative, and shutters normally closing with a movement in one di-

rection of said supporting means and opening with a movement in the opposite direction thereof.

4. In a photographic-printing apparatus the combination of a suitable movable carrier-frame for the negative, shutters normally closing with a movement of the frame from the shutters and opening with a movement toward said shutters, means for locking the carrier-frame for the open position of the shutters, and mechanism for releasing the frame upon conclusion of the printing operation.

5. In a photographic-printing apparatus, the combination of a suitable movable carrier-frame for the negative, shutters normally closing with a movement of the frame away from the shutters and opening with a movement toward said shutters, means for locking the carrier-frame for the open position of the shutters, mechanism for releasing the frame upon conclusion of the printing operation, and means for automatically forcing the frame from the shutters and closing the latter.

6. In a photographic-printing apparatus, the combination of a movable carrier-frame for the negative, shutters normally closing with a movement of the frame in one direction and opening with a movement thereof in the opposite direction, a latch for locking the carrier-frame for the open position of the shutters, mechanism for disengaging the latch upon conclusion of the printing operation, and means for automatically moving the frame to effect a closing of the shutters.

7. In a photographic-printing apparatus, the combination of a movable carrier-frame for the negative, shutters normally closing with a movement of the frame in one direction and opening with a movement thereof in the opposite direction, a latch for locking the carrier-frame for the open position of the shutters, clock-controlled mechanism for disengaging the latch upon conclusion of the printing operation, and means for automatically moving the frame to effect a closing of the shutters.

8. In a photographic-printing apparatus, the combination of a movable carrier-frame for the negative, shutters controlled thereby, a latch for locking the frame for the exposure position of the shutters, a retracting-arm cooperatively connected to the latch, a clock mechanism, means interposed between said mechanism and the retracting-arm for temporarily restraining the action of said arm upon the latch, and for releasing said arm at the conclusion of the printing operation and simultaneously disengaging the latch, whereby the carrier-frame is free to move in proper direction to close the shutters.

9. In a photographic-printing apparatus, the combination of a hinged spring-controlled carrier-frame for the negative, shut-

ters controlled thereby, a spring-latch for locking the frame for the exposure position of the shutters, a clock mechanism, a spring retracting-arm having its free end coupled to the latch, a sleeve capable of independent rotation mounted about the winding-arbor of the clock mechanism but capable of rotation in unison therewith, a dial on the clock mechanism, a pointer on the sleeve co-operating with the dial, a notched disk on the sleeve within the clock-mechanism casing, a wing on the retracting-arm riding on the edge of the disk and adapted to enter the notch when opposite thereto, an oscillating arm coupled to the clock-mechanism escapement, and an intercepting-rod connected to the latch and moving in the path of the oscillating arm upon the engagement of the wing with the disk-notch, the parts operating substantially as, and for the purpose set forth.

10. In a photographic-printing apparatus, the combination of a hinged carrier-frame for the negative, shutters normally closing for an outward swing of the frame and opening with an inward swing thereof, a latch for locking the frame for an open position of the shutters, a time-controlled mechanism for disengaging the latch at the conclusion of a definite period of exposure of the negative, and a spring for forcing the frame outwardly and simultaneously closing the shutters.

11. In a photographic-printing apparatus, the combination of a hinged carrier-frame for the negative, shutters linked to the frame and closed by the outward oscillation thereof, a spring-latch for engaging the frame upon an inward oscillation thereof to effect exposure and a corresponding opening of the shutters, a spring retracting-arm coupled to the latch, a time mechanism for permitting the resiliency of the spring-arm to expend its energy upon the latch and disengage the latter from the carrier-frame, and a spring for forcing the frame to oscillate in proper direction to close the shutters.

12. In a photographic-printing apparatus, the combination of a movable carrier-frame, shutters adapted to exclude the light upon movement of the frame in one direction, and to admit the light upon a movement in the opposite direction; means for locking the carrier-frame for the exposure position of the shutters, and mechanism timed to automatically release the frame and close the shutters at the conclusion of a definite interval of exposure.

In testimony whereof I affix my signature in presence of two witnesses.

JOHN KAUT.
